UNITED STATES PATENT OFFICE

2,196,179

PORTFOLIO, CASE, AND THE LIKE

Charles Doppelt, Chicago, Ill.

Application February 11, 1938, Serial No. 189,954

4 Claims. (Cl. 150—1.6)

This invention relates to portfolios, cases and the like and more specifically to handles and locking means for such articles.

One of the objects of my invention is to provide a portfolio, case or similar article of manufacture which can be carried by a handle and which if desired the handle can be instantly moved into position so as to be hidden from view, to permit the articles to be carried without the use of the handle.

Another object of my invention is to provide a handle for a portfolio, case or the like which can be moved into and out of hand engaging position.

Another object is to provide an improved manner of mounting a handle so that the handle can be moved so as to be entirely hidden within the side walls of the bag or can be moved to be in position to be grasped by the hand.

Another object is to provide an improved manner of supporting a handle so that the handle can be moved into and out of hand engaging position with the support also serving as one element of the locking means.

Another object is to provide a portfolio in which the handle can be positioned to permit a ready opening and closing of the portfolio closure.

In the drawing Fig. 1 is a perspective view of the upper portion of a portfolio showing my invention applied thereto.

Fig. 2 is a side elevation view of the portfolio with my invention and showing in dotted lines the position of the handle when moved out of hand engaging position.

Fig. 3 is a view partly in cross section taken on lines 3—3 of Fig. 2 showing my improved manner of mounting the handle and also the manner of locking the walls of the portfolio together.

Fig. 4 is a top plan view taken on the line 4—4 of Fig. 2 showing the position of the handle when moved out of hand engaging position or in the dotted line position of Fig. 2.

Fig. 5 is a side elevational view partly in cross section of a modified form of locking member.

Fig. 6 is a cross sectional view taken on the line 6—6 of Fig. 5.

The portfolio 10 is formed of two side walls 11 and 12 and the flexible end walls 13 and 14. The bottom of the portfolio is not shown in the drawing. The top of the wall 11 is folded over as at 15 and steel or other stiffening material 16, is placed therebetween. Longitudinally stitched to the wall as at 17 is a web 18 which supports interlocking fastening elements 19. The top of the other wall 12, is also folded over as at 20 and a stiffening material 21, is interposed therebetween. Also longitudinally stitched to the wall section 12 is a web 22, which supports interlocking fastening elements 23, which engage the fastening elements 19, when the co-acting slide 23a is longitudinally moved. The two webs, 18 and 22, when united by the fastening elements, form the top or closure 24 for the portfolio. It will be seen that the closure 24 is spaced below the plane of the upper edges of the wall 11 and 12. This is for the purpose of permitting the handle to be positioned in the manner hereinafter described.

Since both of the handle supports 26 and 27 are identical in construction, a description of one will be sufficient. Firmly secured on the side 15 wall 11 is a pin 28 on which is press fitted a collar 29, a spacing sleeve 30 and another collar 31. Press fitted between the collar 29 and sleeve 30 is an arm 32, and between sleeve 30 and collar 31 is an arm 34. Press fitted on the pin 28 is a male member 35 of the locking means. Referring to the arms 32 and 34, it will be seen that the arms diverge outwardly as at 36 and upwardly as at 37 and then inwardly as at 38, to fit within suitable openings in the handle 39. It will be seen that the overall width of the upward sections 37 is substantially the same as the width between the insides of the walls 11 and 12 when the walls are locked. Permanently secured to the wall 12 are the female members or sockets 40 and 41 into which the male members are pressed when it is desired to lock the walls together. It will be seen that the sleeves, collars, and arms can be rocked or rotated axially with the pin but cannot be removed therefrom.

If desired, the portfolio can be carried as a bag or satchel with the handle in hand engaging position in the position shown in Figures 1, 2 and 3. However, if it is desired to carry it as a portfolio, without the handle, the handle can be moved to assume the position shown in the dotted lines in Figure 2 and in full line in Figure 4 in which the arms 32 and 34 and handle 39 assume a substantial horizontal position, with the arms at one end under the handle. However, if the handle were moved in the opposite direction, the arms at the other end will be positioned under the handle. In either of these positions, the top of the handle will be below the plane of the top edges of the walls and will be thus hidden from view. By virtue of the fact that the overall width of the arms is substantially the same as the width on the inside of the walls, when the walls are locked together, the handle when moved to the position 55

shown in Figure 4, will be retained therein by the close fit therebetween.

Referring to the modified form of handle support shown in Figures 5 and 6, I provide a pin 50, which fits within the sleeve 51. The supports for the handle are mounted similar to that described in connection with Figures 1 to 4 inclusive. The sleeve 52 extends beyond the wall 11 to form a male member 51a which has an annular recess 52, which is to be engaged by the locking member generally indicated as 53. The locking member 53 is formed of two plates, 54 and 55, which are secured together to provide a housing for the latch member 56, which is tensioned upwardly by a spring 57. The plate 54 has projections 54a which pass through suitable openings in the plate 55, and through the wall of the portfolio and through the supporting plate 55a on the opposite side of the wall and are bent thereagainst to hold said unit in place. It will be seen that all the plates as well as the wall have aligned openings for the passage therethrough of the male member and that after the male member is in the position shown in Figure 6, the latch member 56, will be urged upwardly to engage the male member in the recess and lock the male member against withdrawal unless the plate is depressed by means of its flange 58.

It will be understood that various modifications, and changes can be made without departing from the spirit and scope of my invention. What I desire to secure by Letters Patent is:

1. In a portfolio of the class described comprising side walls having marginal portions at the top thereof, a web having interlocking fastening elements secured to each of said walls and when interlocked arranged to form a channel with said marginal portions, transversely extending handle supporting elements secured on one of said marginal portions below the plane of the top edge thereof, locking members secured on the opposite marginal portion and adapted to releasably engage the handle supporting elements, handle engaging means swingably supported by said elements, a handle member secured to said means and arranged to be longitudinally movable to a position between said marginal portions within said channel and below the plane of the top marginal edge thereof, said handle member ar-

ranged to be further movable to assume a hand engaging position above the plane of the upper edge of said marginal portions.

2. In a portfolio of the class described comprising side walls having longitudinally extending marginal portions, transversely extending handle supporting elements permanently secured to one of said marginal portions below the plane of the top edge thereof, locking members secured on the opposite marginal portion and adapted to releasably engage the handle supporting elements, handle engaging means swingably supported by said elements, a handle member mounted on said means and arranged to be longitudinally movable to a position between said marginal portions and below the plane of the top marginal edge thereof, said handle member arranged to be further movable to assume a hand engaging position above the plane of the top edge of said marginal portions.

3. In a portfolio of the class described comprising side walls having longitudinally extending marginal portions at the top thereof, handle supporting elements secured to one of said marginal portions below the plane of the top edge thereof, cooperating receiving elements secured on the opposite marginal portion and adapted to releasably engage said handle supporting elements, handle engaging means swingably supported by said elements, a handle mounted on said means and adapted to be longitudinally movable to assume a position above and below the plane of the top edge of said marginal portions.

4. In a bag of the class described comprising side walls having longitudinally extending marginal portions forming the mouth of said bag, transversely extending handle supporting elements secured on one of said marginal portions below the plane of the top edge thereof, locking elements secured on the opposite marginal portion to receive said handle supporting elements and retain said marginal portions in locked position, handle engaging means swingably supported by said elements, a handle member secured to said means and of a transverse width so that it can be longitudinally moved between said marginal portions below the top edges thereof.

CHARLES DOPPELT.
